FACING PLATE

Edward C. Hallock, 86 Woodland Ave., Summit, N.J.

Filed Dec. 20, 1963, Ser. No. 77,880

Term of patent 14 years

(Cl. D13—1)

FIG.1.

FIG.2.

FIG.3.

FIG.4.

I claim:

The ornamental design for a facing plate, as shown.
